(57) **CLAIM**

The ornamental design for a little tote lid with stacking supports, as shown and described.

(21) Appl. No.: **29/542,963**

DESCRIPTION

(22) Filed: **Oct. 20, 2015**

FIG. 1 is a top perspective view of a little tote lid with stacking supports;

(51) LOC (10) Cl. 03-01

FIG. 2 is a bottom perspective view of the little tote lid with

(52) U.S. Cl.

stacking supports of FIG. 1;

USPC **D3/303**

FIG. 3 is a top plan view thereof;

(58) **Field of Classification Search**

FIG. 4 is a bottom plan view thereof;

USPC D3/318

FIG. 5 is a right side elevational view thereof; and,

CPC B62B 2206/006; B62D 1/22; B62D

2543/00194; B62D 2543/00296

FIG. 6 is a front elevational view thereof.

See application file for complete search history.

A left side elevational view is not shown because it is a mirror image of the right side elevational view shown in FIG. 5. A rear elevational view is not shown because it is a mirror image of the front elevational view shown in FIG. 6. The ornamental design which is claimed is shown in solid lines in the drawings.
